RADIO RECEIVER

Application filed October 17, 1930. Serial No. 489,272.

- This invention relates to improvements in radio receivers particularly to a device designed to improve the control of the overall amplification of the received signal.
- 5 It is well known that the signal intensity at the antenna of a radio receiver varies from a few microvolts to several volts depending upon whether the receiver is located in the immediate vicinity of the transmitting station or at a distance of say one thousand or more miles. This makes the control of the volume of the amplified signal very difficult, since the total amplification of the signal has to be varied over a wide range.
- 10 15 It has been the practice to control the signal volume delivered by a receiver by attenuating the signal by means of suitable resistances at various stages of the amplifier or at the antenna coil or to attenuate the signal at the antenna by a separate "local-distance" switch which may change the tap to the antenna coil or insert a condenser in series with the antenna. These expedients, however, have introduced complications in the structure of the receiver and in its control and have increased the cost of producing the receiver and for these reasons are undesirable.
- 20 25 30 One of the principal objects of the present invention is to provide a volume control for radio receivers having a single operating knob or element which, when turned to maximum volume position, will actuate a switch or its equivalent to increase the sensitivity of the receiver for distance reception and which when moved to the minimum volume position will reversely actuate the same switch to decrease the sensitivity of the receiver for local reception. And the same operating element or knob is capable of effecting smooth and accurate regulation of the volume whether the receiver is in a condition of maximum or minimum sensitivity.
- 35 40 45 Broadly, the present invention resides in a radio receiver having means, usually but not necessarily, cooperable with the antenna for varying the volume of the signal impressed on the receiver, a local-distance switch regulating the action of said means and operable in one position to put the receiver in a condition of maximum sensitivity for dis-
- tant reception and in another position to put the receiver in a condition of minimum sensitivity for local reception, a manually operable volume control device usually in the form of a variable resistance and effecting smooth and accurate regulation of the volume whether the receiver is in a condition of maximum or minimum sensitivity and interengaging means between the manually operable volume control device and the local-distance switch whereby when the manually operable device is moved to its maximum volume position it will automatically throw the local-distance switch into distance reception position and when the manually operable volume control device is moved to its minimum volume position it will automatically and reversely actuate the local-distance switch to decrease the sensitivity of the receiver for local reception. The invention is susceptible of embodiment in any of the various types of receivers and while in the present application three embodiments are illustrated it is to be understood that the particular types selected merely illustrate the invention and are not intended to restrict it to these particular types. For example, the manually operable volume control device utilized to effect a graduated regulation over the volume when the local-distance switch is in either position may consist of a potentiometer connected across the antenna receiving coil, a variable resistance connected with the grid circuits of the radio frequency amplifier to provide a variable negative potential for the grids with respect to their cathodes or a variable potentiometer resistance connected across the secondary of an audio transformer. The local-distance switch may carry out its function by connecting the antenna to its receiving coil directly in one position or through a condenser connected in series between the antenna in its other position. Then again the local-distance switch may be utilized to change the coupling of the first tuned vacuum tube circuit to the antenna, that is, it may be applied to the so-called C-bias resistance utilized for volume control purposes. Where the manually controlled volume device consists of a variable potentiometer resistance connected

across the secondary of an audio transformer its movable contact is operatively interconnected with the local-distance switch and the local-distance switch is connected up to the 5 primary coil of the antenna whereby the manually controlled device automatically throws in all of the windings of the coil for distant reception and cuts out some of these windings and utilizes only a portion of the 10 coil for local reception.

Other objects and advantages reside in certain novel features of the construction, arrangement and combination of parts which will be hereinafter more fully described and 15 particularly pointed out in the appended claims, reference being had to the accompanying drawings, forming a part of this specification, and in which:

Figure 1 is a diagrammatic view showing 20 the invention embodied in a radio receiver having a volume control of the type wherein a potentiometer resistance is employed across the antenna receiving coil;

Figure 2 is a similar view showing the 25 invention as applied to the so-called C-bias resistance for volume control purpose;

Figure 3 is a diagrammatic view showing the invention embodied in a radio receiver of the type in which volume control is effected 30 by means of potentiometer resistance incorporated in the audio amplifier and by means of an arrangement of circuits for changing the coupling of the antenna coil with the first amplifier;

35 Figure 4 is a view partly in elevation and partly in transverse section showing one construction of manually operable volume control device, local-distance switch and interconnecting means between the device and 40 switch;

Figure 5 is a view in elevation looking toward the left hand side of Figure 4 with parts broken away for the sake of illustration;

45 Figure 6 is a view similar to Figure 5 but showing a different position of the parts;

Figure 7 is a view similar to Figures 5 and 6 but showing the rear cover plate removed; and

50 Figures 8, 9 and 10 are detail perspective views showing the cover plate and local-distance switch, the movable arm of the manually operable volume control device and the rocking contact thereof, respectively.

55 Referring to Figure 1, the potentiometer resistance 1 is shown connected across the antenna receiving coil 2 which furnishes the input voltage to the first vacuum tube 3 of a radio receiver. The adjustable contact 4 on the potentiometer resistance can be moved from one end of the resistor to the other. A projection 5 on this movable contact is arranged to engage the pawls 6 or 7 of the switch lever 8 when the arm is contacting at 60 either end of the resistance 1. The lever 8 is

pivoted at the point 19. When the contact 4 is moved to the upper end of the resistance 1, the switch lever 8 is moved so that element 9 moves down into electrical contact with 10. In this position the antenna conductor 12 is connected through 9, 10 and conductor 13, directly to the upper end of the coil 2. Since the contact 4 is at the upper end of resistance 1, this results in the grid of the vacuum tube 3 being connected directly to the antenna and receiving the full potential across the coil 2. This evidently is the condition for maximum sensitivity of the receiver and corresponds to maximum volume of signal output. With the switch contacts 9 and 10 connected we, 70 therefore, have the so-called "distance" position of this switch. If the volume is too great, it can then be adjusted by moving contact 4 down, which, however, still leaves the contacts 9 and 10 connected in the "distance" position.

If the operator happens to tune in a local station when the receiver is in the above condition of maximum sensitivity, a very loud signal will result. The operator will, therefore, move contact 4 down on resistance 1, decreasing the volume until the maximum decrease obtainable with the volume control resistance is achieved, which is when contact 4 reaches the bottom of resistance 1. When this happens, however, the projection 5 engages the pawl 7 and throws the switch contacts 9 and 11 into connection. This throws the condenser 14 in series with the antenna and coil 2, thereby decreasing the potential across the coil 2 and also the sensitivity of the receiver. This connection of contacts 9 and 11 corresponds to the "local" position of the switch. If the operator now desires to increase the signal volume above the level obtainable under the above described conditions, he merely moves contact 4 up on resistance 1, until the desired volume is obtained. In the above described manner the logical sequence of operations on the volume control of the receiver produces the required functioning of the "local-distance" switch 90 automatically.

Figure 2 shows an arrangement of circuits wherein the same combination of volume control resistance and switching device changes the sensitivity of the receiver by changing the coupling of the first tuned vacuum tube circuit to the antenna. In Figure 2 the rheostat 15 is equipped with a contact 4 having a projection 5 exactly similar to the contact arm of Figure 1. In this circuit resistance 15 provides a variable negative potential for the grids of the radio frequency amplifier tubes 16 and 17 with respect to their cathodes. The higher contact 4 is moved on resistance 15 the greater the negative potential of the grids with respect to their cathodes. It is, of course, understood that the current 100 from the cathodes of more than two tubes 110 115 120 125 130 135 140 145 150 155 160 165 170 175 180 185 190 195 200 205 210 215 220 225 230 235 240 may be allowed to pass through the resistance 15, although the diagram of Figure 2 illustrates the principle as applied to a two tube radio frequency amplifier. When the rheostat arm 4 is moved up to include maximum resistance projection 5 engages pawl 7 to cause contacts 9 and 11 of the switch to be connected together, and the receiver is in a condition of minimum sensitivity for local reception since the number of turns in the primary of the antenna coupling transformer is decreased. Conversely, when the contact 4 is moved down on the rheostat to increase the volume when seeking for distant stations, the projection 5 engages pawl 6 to cause the switch contacts 9 and 10 to be connected together at the end of the travel of 4. This corresponds to the "distance" position of the switch and after finding the desired station the volume can again be adjusted by moving 4 up until the desired signal volume is obtained.

It will be noted from the above description that the "local-distance" switch always remains in the position into which it is thrown at the ends of the travel of the rheostat arm, so that volume can be independently controlled in either the "local" or "distance" range of the receiver.

Referring to Figure 3, the primary 22 of an antenna coupling transformer is shown tapped by conductor 23. The conductor 23 leads to contact 11 on the local-distance switch which is operatively related to the potentiometer resistance 25. Contact 10 of the switch is connected to the lower end of the antenna coil 22. Conductor 26 connects the switch arm to ground.

The potentiometer resistance 25 is connected across the secondary of the audio transformer 27. The adjustable potentiometer contact 4 bearing on the resistance 25 is connected to the grids of the last audio amplifier tube 28. In this manner the volume of sound output on the loud speaker may be increased or decreased as contact 4 is moved to the left or right, respectively.

When the contact 4 is moved to its extreme left position, the projection 5 engages the pawl 6 and throws the switch contact 9 into connection with the contact 10 so that increased volume or maximum volume is had for when contacts 9 and 10 engage the entire antenna coil 22 is in series with the antenna and ground. The volume may now be cut down by moving the contact 4 to the right as viewed in Figure 3. If the receiver is tuned for local reception and intermediate adjustment of the contact 4 does not provide the desired reduction in volume the movement of contact 4 to its extreme right hand position as viewed in Figure 3 will bring its projection 5 into engagement with the pawl or dog 7 thereby swinging the movable switch contact 9 into engagement

with contact 11, and consequently connecting the upper portion only of the primary coil 22 in series with the antenna and ground. This puts the receiver in condition for local reception or in a condition of minimum sensitivity and does this with the contact 4 positioned so that adjustment of it to the left will increase the volume if increase be desirable.

While Figure 3 shows only a single radio frequency stage, a detector and a single audio frequency stage, it is, of course, understood that any desired number of either radio frequency or audio frequency stages may be added to the circuit shown without changing the principle of operation of the device described.

Referring now to Figures 4 to 10, inclusive, there is shown one structure embodying a manually operable volume control device, a local-distance switch and an interconnecting means between these elements. The volume control device is of the type disclosed in Patent 1,653,745, granted December 27, 1927, to Erwin R. Stoekle.

As illustrated, the volume control device includes a housing 30 preferably constituted of bakelite or hard rubber composition. The open rear end of the rear portion of the housing is closed by a cover plate 31. A graphite resistor 32 is mounted within the housing and corresponds to the resistor of potentiometer of Figure 1, or to the resistance 15 of Figure 2 or to the resistance of potentiometer 25 of Figure 3. The ends of the graphite resistor 32 are electrically connected with terminals 33 and 34 to which the conductors are attached. The movable contact is in the form of a rockable strip 35, the strip 35 being almost a complete circle and having inwardly extending arms 36 provided with an integral fork 37 and an integral attaching strip 38. Strip 38 is connected to a terminal 39 which is insulated, of course, from the terminals 33 and 34. The fork 37 engages between insulating washers 39 carried by a flange ring 40 which is mounted on the operating shaft 41. As will be seen from Figure 4, the attaching strip 38 is fastened by the rivet 38' which connects it to its terminal 39 on a boss or lug 39' and consequently the disc-like movable contact 35 is biased to a position spaced from the resistor 32 and any portion of this strip 35 is engaged with the resistor under the influence of a rotatable switch arm 42 fixed to the inner end of a shaft 41 and having a button 43 adapted to slide around the strip 35 and press any portion of this strip against the portion of the resistor 32 underlying the same. For limiting the motion of the switch arm 42 and preventing its button 43 from running off of the strip 35, the hub of the arm 42 is slotted as at 45 and a fixed stop lug 46 carried by the base projects into this

slot. The lug 46 engages the ends of the slot to positively limit movements of the switch arm.

The contacts of the local-distance switch, 5 designated at 10 and 11, are mounted on the inside of the cover plate 31 and connect with terminals or binding posts 47 and 48 mounted on the outside of the cover plate. The movable contact of the local-distance switch 10 is designated at 9 and is pivotally connected as indicated at 50 to the cover plate. The movable contact 50 is in electrical connection with the cover plate but the contacts 10 and 11 and their terminals 47 and 48 are electrically insulated from the cover plate. The binding post of the movable contact 9 is designated at 51 and is directly connected to the cover plate 31. The automatic operation of the local-distance switch from the 20 manually operable controlled device may be effected by providing a projection 55 on the movable switch arm and disposing this projection to engage a pawl or lug 56 when the switch arm is at the limit of its movement in one direction and to engage a pawl or lug 57 when the switch arm is at the limit of its movement in the opposite direction. It is to be understood that the projection 55 engages either lug 56 or 57 when it is just approaching 25 the end of its motion in one direction and when the switch arm still may be moved sufficiently to shift the movable contact 9 from contact 10 to contact 11 or from contact 11 to contact 10, as the case may be.

30 35 It is to be understood that the structure shown in Figures 4 to 10 is merely illustrative of one embodiment of the invention and that various changes in the sizes, shape, form and arrangement of the parts may be made 40 without departing from the spirit of the invention or the scope of the subjoined claims.

It is obvious that the contacts 10 and 11 and the terminal 51 of the local-distance switch may be connected up in the receiver 45 as illustrated in Figures 1, 2 or 3, or in any other appropriate manner. Likewise the terminals 33, 34 and 39 of the variable resistance or potentiometer are connected up in the receiver in the manner illustrated in Figures 50 1, 2 or 3, or in any other appropriate manner.

The invention claimed is:

1. A radio receiver having means co-operative with the antenna for varying the volume of the signal impressed on the receiver, a 55 local-distance switch regulating the action of said means and operable in one position to put the receiver in a condition of maximum sensitivity for distance reception and in another position to put the receiver in condition 60 of minimum sensitivity for local reception, a manually operable volume control device for effecting smooth and accurate regulation of the volume whether the receiver is in a condition for maximum or minimum sensitivity and interengaging means between the

manually operable volume control device and the local-distance switch whereby when the manually operable device is moved to its maximum volume position it will automatically throw the local-distance switch into distance reception position and when the manually operable control device is moved to its minimum volume position it will automatically and reversely actuate the local-distance switch to decrease the sensitivity of the receiver for local reception. 70 75

2. A radio receiver having means including a local-distance switch and operable with the local-distance switch in one position to put the receiver in a condition for maximum sensitivity for distance reception, and in another position to put the receiver in a condition of minimum sensitivity for local reception, a manually operable control device associated with the receiver for effecting graduated and accurate regulation of the volume when the receiver is in a condition of maximum or minimum sensitivity and means interconnecting the manually operable control device and the local-distance switch when the manually operable control device approaches either of its extreme positions whereby the manually operable control device automatically operates the local-distance switch when moved to either extreme position. 80 85 90 95

3. A radio receiver having a local-distance switch, a manually operable volume control, and means actuated by the manually operable volume control for automatically moving the local-distance switch to one position when the manually operable volume control approaches one predetermined position and for throwing the local-distance switch to another position when the manually operable volume control is moved to a second predetermined position. 100 105

4. A radio receiver provided with manually controlled means for attenuating the strength of the amplified received signal, said attenuating means including a switching means and means automatically operated by said manually controlled attenuating means to put said receiver in a condition of maximum sensitivity for distant reception or in a condition of lesser sensitivity for local reception. 110 115

5. A radio receiver having a volume control device, a local-distance switch, and means operatively relating said volume control device and said local-distance switch whereby said switch will be automatically thrown into the distance reception position when said volume control is moved to its position of maximum volume and will remain in this position until said volume control is moved into its position of minimum volume whereupon said switch will be thrown into its local reception position and will so remain until said volume control is again moved to its maximum volume position. 120 125

6. A radio receiver including a variable resistance for attenuating the signal, means 130

for varying said resistance, means cooperable with an antenna receiving coil for varying the volume of the signal impressed on the receiver and a switch controlling the action of said means and automatically operated by said first named means.

7. A radio receiver provided with a volume control device operatively related to a local-distance switch and adapted to throw said switch into its distance and its local position at the maximum and minimum positions, respectively, of said volume control whereby the volume of the amplified receiver signal may be regulated independently over the entire local range of sensitivity of the receiver and over the entire distance range of sensitivity of the receiver.

8. A radio receiver including an antenna, an antenna receiving coil, a vacuum tube, a potentiometer resistance connected across the antenna receiving coil and having a movable contact connected to the vacuum tube to supply the input voltage thereto, a condenser and a switch for connecting the antenna to its receiving coil through the condenser and for connecting the antenna directly to its receiving coil and cooperating means between the movable contact of the potentiometer and the switch for causing the switch to be automatically operated when the movable contact approaches either of its extreme positions.

9. A radio receiver including a radio frequency amplifier vacuum tube, a so-called variable C-bias resistance for varying the negative potential of the grid of said tube with respect to its cathode, an antenna coupling transformer, electrical connections for connecting the entire primary of said transformer or a portion only thereof to the ground and a switch for making and breaking said circuits and connected with the variable resistance so as to be operated when said variable resistance is in either of its extreme positions.

45 10. A radio receiver including an antenna coupling transformer, an audio transformer, a variable potentiometer resistance connected across the secondary of the audio transformer, electrical connections for connecting the entire primary of the antenna coupling transformer or a portion only thereof to the ground and a switch controlling said electrical connections and automatically operated by the potentiometer.

55 11. A radio receiver having a local-distance switch including a movable contact provided with spaced projections, and a manually operable volume control having a movable element provided with a projection engageable with one of the projections of the contact switch in one position of the manually operable volume control and engageable with the other projection of the switch in another position of the volume control whereby the local-distance switch is automatically operated

from the manually operable volume control. In witness whereof, we hereto affix our signatures.
